(57) **CLAIM**

The ornamental design for a spoke for a vehicle wheel, as shown and described.

DESCRIPTION

FIG. 1 is a perspective view taken from the left hand side of my new spoke for a vehicle wheel; and,

FIG. 2 is a front elevational view thereof.

The broken lines adjacent to the spoke member on the wheel and in the center hub area define the bounds of the claimed design and form no part thereof while the remaining broken lines depict environment for illustrative purposes only and form no part of the claimed design.
